TUBE-MAKING MACHINE

Karl E. Garling, Newark, N. J., assignor to Soda
Straw Manufacturing Corporation, Newark,
N. J., a corporation of New Jersey

Application July 12, 1933, Serial No. 680,032

27 Claims. (Cl. 164—61)

This invention relates to improvements in tube-making machines and finds as one particular utility, the manufacture of soda straws.

Among the principal objects which the invention has in view are:—To provide an improved machine for the manufacture of tubes, such as soda straws; to simplify the mechanism and operation over the constructions and procedures of present-day machines; to avoid delays resulting from inadvertent unwinding of the tube or straw adjacent the cutter; to lead the tube or straw to the cutter with minimum tendency to untwist; to steady the straw while being cut; to permit the straw to be moved by the knife in the direction of rotation of the knife while being cut; to utilize the moment of force of the knife translating the straw in the direction of movement of the knife to also carry the straw into the knife for severing purposes; to provide for proper formation of the straw preparatory to cutting the same; to obtain a compound movement of the straw translating mechanism; to reduce the number and complexity of operating parts; to secure simplicity of construction commensurate with efficiency and acceptable engineering; and to obtain other advantages and results as may be brought out in the following description.

Drawings:

Figure 1 is a plan of a machine constructed in accordance with the present invention;

Figure 2 is an elevation of the cut-off mechanism partially in section as upon line 2—2 of Fig. 1;

Figure 3 is a sectional elevation at right angles of Fig. 2, partially in section as upon line 3—3 of Fig. 1;

Figure 4 is an end elevation looking in the opposite direction from that of Fig. 3;

Figure 5 is an elevation similar to that of Fig. 4 showing the straw guide in a position advancing the straw toward the cutter;

Figure 6 is a similar view showing the straw just after it has been cut;

Figure 7 is a longitudinal sectional view of the straw guide showing the same tilted in the position where the straw is being cut as in Fig. 6; and

Figure 8 is an end view of a modified construction of cut-off mechanism utilizing the same straw guide and movement in association with a pair of knives and a modified construction of straw support associated with the knives.

Description:

In the specific embodiment of the invention illustrated in said drawings, and referring ini-

tially to the general assembly shown more particularly in Fig. 1, the reference numeral 10 designates a suitable base or bed upon which the several parts are mounted. Above this base, near the edge, which for convenience may be termed the rear of the machine, is a drive shaft 11 adapted to be rotated by means of a pulley 12 from any suitable source of power. This shaft 11 is shown geared to a parallel cam shaft 13 upon which is mounted a cam 14 for reciprocating purposes and a cam 15 for dipping the straw into the knife as will be described in greater detail hereinafter.

Parallel to the drive shaft 11, between it and the front of the machine, is carried a winding 15 mandrel 16 upon which the strips of paper of which the straw is manufactured are continuously wound. This operation is old and well known in the art and is very commonly carried out by means of an endless belt 17 twisted around the mandrel 20 and carried by horizontally disposed pulleys 18, 19. The strips of paper are ordinarily obtained in rolls and these rolls carried by a bracket 19 so as to be fed to the mandrel at an angle opposite to the angle of the endless belt, with one 25 of the strips of paper in contact with a glue drum 20, the lower part of which dips into a glue pot 21. The drum 20 is driven at a predetermined rate with respect to the endless belt 17, preferably having a positive drive (not shown) 30 from the drive shaft 11. The belt pulley 18 next the drive shaft is likewise positively driven, so that both pulleys and the glue drum are positively actuated at the proper speed so as not to place any undesired strain upon either the 35 endless belt or upon the strips of paper of which the straw or tube is being made.

By virtue of the endless belt 17, the strips of paper are formed into a spiral tube and forced continuously from the end of the mandrel to 40 the cutting mechanism for severing the formed tube into substantially equal lengths. It is in this cutting mechanism that the present invention inheres more particularly, and will now be described in greater detail, reference being had 45 to all of the figures of the drawings.

As the paper strips are formed into a spiral tube, such as indicated at 22, and forced from the end of the mandrel, said tube, which for the sake of clarity will be hereinafter referred to as 50 the straw, enters into the receiving end of a guide 23, here shown as a tube with an internal diameter slightly greater than the outside diameter of the straw so as to avoid any unnecessary frictional contact between the straw and the said 55

tube or guide 23. The end of this tube 23 is pivotally mounted so that the opposite end may be swung with a compound movement. For accomplishing this purpose, the pivotal mounting is 5 here shown as of a universal type, thereby enabling the tube to swing as required either up or down or back or forth or in combination of these movements. In carrying out this feature, a flange 24 is carried by the tube 23 at its pivoted end, this flange being positioned in a socket 25 within a bracket 26 and confined loosely within that socket by face plates 27, 27 secured to the bracket. Likewise, these face plates 27 have holes therein for the tube 23, said holes being of greater 10 diameter than the tube, thus enabling the tube and flange to wobble to the desired extent. It will be observed by utilizing the structure so far described, that the end of the tube 23 toward the mandrel retains substantially a fixed relation with 15 respect to the mandrel and consequently the straw will feed from the mandrel to the guide with minimum distortion and will therefore have little if any tendency to untwist.

The forward or delivery end of tube 23, that is, 25 the end furthest away from the mandrel has means connected therewith for both dipping the straw into engagement with a knife 28 and for moving the straw in the direction of rotary movement of the knife while the straw dips into the 30 knife. As a means for accomplishing this compound movement, I employ in association with previously mentioned cam 15, an arm 29 with a roller 30 thereon engaging the cam surface such that the arm is periodically swung. This arm 29 is arranged to swing a connected arm 31 shown 35 projecting toward the front of the machine with its forward end overlying the path of the straw. In this forward end of arm 31 is rotatably mounted a rocker shaft 32 which extends substantially 40 a parallel to the straw thereunder. It will be observed that as the arm 31 swings up or down, said rocker shaft 32 is likewise moved bodily in a corresponding direction. This rocker shaft 32 extends from arm 31 in a general direction toward 45 the mandrel, and at its receiving end toward the mandrel is above and in plan, overlaps the outer end of the tube or guide 23. A connection is made at these overlapping ends between the rocker shaft 32 and the tube guide 23 by a link 50 50 transverse to both of those parts and securely affixed at least with respect to the rocker shaft. It will accordingly be observed that as arm 31 swings downwardly rocker shaft 32 is bodily depressed, thereby carrying link 33 downward and 55 as a result, swings or dips the forward end of tube or guide 23 downwardly. Lost motion in the guide is overcome by a tension spring 33 hooked at its upper end on said guide and secured at its lower end in suitable manner to bracket 26. 60 Simultaneously with the dipping operation thus obtained for the forward end of tube guide 23, said guide is also swung laterally. For carrying out this feature, I have shown a spur gear 34 mounted upon rocker shaft 32 at the end thereof 65 next to arm 31 and secured to the shaft as by a set screw 35 so that any rotation of the gear will obtain a corresponding rotation of the rocker shaft. The spur gear is in mesh with a vertically disposed rack 36 carried by a bracket 37, the 70 lower end of which is secured to the base 10 of the machine. In passing, it may be observed that this bracket 37 preferably is sufficiently resilient to enable the rack to be resiliently pressed toward the gear and thereby maintain a positive meshing as well as to decrease noise and avoid unneces-

sary play between the rack and gear and secure precision in the movement of the shaft 32. It will be observed that as arm 31 depresses, gear 34 rides down rack 36 and thus obtains a partial rotation of shaft 32 while said shaft is being bodily depressed. As a result, link 33 is swung toward the front of the machine and imparts a corresponding downward and forward movement of the tubular straw guide 23. Knife 28 is rotated through the agency of a motor 38 and belt 39 in a 10 direction such that the top part of the blade is moving in the same general direction as the combined dipping and forward movement of the straw guide; that is to say, the upper part of the knife has a rotary movement toward the front 15 of the machine.

The knife 28 is mounted to reciprocate back and forth in synchronized relationship to the dipping of the straw guide so that the straw will be dipped into the blade at a time when the straw 20 and knife are moving in the same direction and at substantially the same rate, it being noted that the delivery end of the guide 23 is spaced from the path of the knife to provide between the tube and the knife an extended gap to insure the easy 25 flexing of the straw between the tube and the cutter, and also to facilitate access to the thus exposed portion of the straw as occasion may require. As here shown, the knife is mounted upon a spindle 40 carried by a bearing 41 formed 30 as part of a carriage 42 which has rods 43 parallel to the spindle 40 in turn mounted in bearings 44 and 45, thereby guiding and supporting the carriage. If so desired, additional tracks 46 may be provided to partially support the carriage 35 and relieve the rods 43 of the downward thrust occurring during operation. From one side of the carriage, that is, toward the back of the machine, is mounted a suitable roller 47 which rides within the groove of reciprocating cam 14.

Associated with the knife 28 and mounted to reciprocate therewith, is a bifurcated platen or cutting table 49, so that part of the cutting table is at one side of the knife and part of it is at the other side of the knife. According to the present disclosure I have shown this bifurcated platen 49 sloping at an angle of substantially twenty-five (25°) degrees to the horizontal and having a lip or end portion 50 of itself directed toward the rear of the machine sloping at substantially forty-five (45°) degrees to the horizontal, this latter portion for convenience being referred to as the lip of the table. The slope of this lip 50 is directed downwardly forward, faces toward the rear of the machine and is shown co-extensive with that part of the platen above the edge of the knife. In operation, the straw is dipped and swung forwardly to substantially maintain it in contact with this lip portion 50 of the platen during the presentation of the straw to the knife for severing purposes. The knife and lip portion 50 of the platen form a converging wedge shape, with the knife rotating in a direction toward the apex of the wedge shape. Consequently, the straw, which travels 55 along one face of the wedge and rotates with peripheral contact in substantially the direction of movement of the periphery of the knife is engaged by the knife and cut with more certainty and less distortion than if the movement of the straw were at a right angle to the direction of movement of the cutting edge. The tendency of the knife to draw the straw along with it is utilized to maintain the straw against the platen, and I have found it of particular utility to util- 60 65 70 75 80 85 90 95

ize the two angles above mentioned for the straw-engaging face of the platen. This structure enables the straw to ride on the cutting edge of the knife, according to the keenness of the knife, as long as necessary to obtain entry of the cutting edge, and avoid any crushing of the straw onto the knife, which, when the knife has become dulled, injures the straw. Dipping of the tube guide merely presents the straw to the knife but does not enforce cutting or passage of the straw further than the cutting edge, particularly since the tube guide is spaced from the knife considerably more than the diameter of the straw so that the straw may flex rather than crush. The rotation of the straw tends, during the depressed period, to roll the straw upon the platen toward the knife, and maintaining a constant presentation of the straw to the cutting edge until the straw is severed. Consequently, by the present invention, a knife may be retained in use for a much longer period than has heretofore been possible before its removal to sharpen is necessary.

25 While it is apparently not a prerequisite to the usual functioning of the machine, nevertheless, it appears desirable to provide a shield 51 below the platen 49 and spaced sufficiently therefrom so that the straw may pass between the shield and platen while the straw is being severed. This shield will serve to steady the straw should occasion require and prevent undue sagging should the straw show such a tendency. It may furthermore be noted that the structure of platen has a great advantage in the 30 operation of the machine and will be especially appreciated by the operator at times when the straw unwinds. There are occasions when the straw unwinds and the machine has to be stopped to start the straw properly. This unwinding 35 most frequently occurs in the gap between the guide and the knife. By using an open platen such as above described, the unwound strips are 40 readily removed and the straw started again over the platen without any difficulty.

45 My invention is not to be understood as con-
fined to the use of a single knife, but if so de-
sired, the straw may be severed by a pair of
overlapping knives with the dipping and swing-
ing of the straw obtaining a presentation of the
straw to the knives at the point where they be-
gin to overlap. Such a structure is indicated in
50 Fig. 3 wherein a pair of rotary blades or knives
52, 52 are provided with the overlapping portion
thereof in flatwise engagement. A platen 53
55 is provided to support the straw as may be found
necessary, the platen in this instance being shown
with curved surfaces following the contour of
the blades for such part thereof as necessary for
supporting the straw during its presentation to
60 the blades. A straw guide 23 similar to the one
already described will dip and swing the straw
22 into the converging knives as will be readily
understood.

Obviously other detail changes and modifications may be made in the construction and use of my improved cut-off mechanism without departing from the spirit or scope of the invention, and I do not wish to be understood as limiting myself to the exact construction shown or described except as set forth in the following claims when construed in the light of the prior art.

I claim:

1. A cut-off mechanism comprising in combination with means for feeding a straw continuously, a knife having a cutting edge moving

transversely to the path of the straw, and means for moving the straw into the knife with a component of movement in the direction of the movement of the knife edge where engaged by the straw.

2. A cut-off mechanism comprising in combination with means for feeding a straw continuously, a knife having a cutting edge moving transversely to the path of the straw, means for moving the straw into the knife with a component of movement in the direction of the movement of the knife edge where engaged by the straw, and a platen adjacent the knife for steady-
ing the straw while being cut. 10

3. A cut-off mechanism comprising in combination with means for feeding a straw continuously, a knife, having a cutting edge moving transversely to the path of the straw, means for moving the straw into the knife with a component of movement in the direction of the movement of the knife edge where engaged by the straw, and a platen adjacent the knife sloping in the direction of movement of the knife for steadyng the straw while being cut. 15 20.

4. A cut-off mechanism comprising in combination with means for feeding a straw continuously, a knife having a cutting edge moving transversely to the path of the straw, means for moving the straw into the knife with a component of movement in the direction of the movement of the knife edge where engaged by the straw, and a platen adjacent the knife, said platen having a changing slope in the direction of movement of the knife for steadyng the straw while being cut. 25 30 35

5. A cut-off mechanism comprising in combination with means for feeding a straw continuously, a knife having a cutting edge moving transversely to the path of the straw, means for moving the straw into the knife with a component of movement in the direction of the movement of the knife edge where engaged by the straw, and a platen adjacent the knife, said platen providing a lip portion with a slope in the direction of movement of the knife at an acute angle and a body portion with a slope at a more acute angle for steadyng the straw while being cut. 40 45

6. A cut-off mechanism comprising in combination with means for feeding a straw continuously, a knife having a cutting edge moving transversely to the path of the straw, means for moving the straw into the knife with a component of movement in the direction of the movement of the knife edge where engaged by the straw, and a platen adjacent the knife, said platen providing a lip portion with a slope in the direction of movement of the knife at an acute angle and a body portion with a slope at a more acute angle for steadyng the straw while being cut, said angles changing at substantially the point of intersection of the knife edge with the platen. 50 55 60

7. A cut-off mechanism comprising in combination with means for feeding a straw continuously, a knife having a cutting edge moving transversely to the path of the straw, and a platen having a flat straw-engaging face for supporting the straw while being cut. 65

8. A cut-off mechanism comprising in combination with means for feeding a straw continuously, a knife having a cutting edge moving transversely to the path of the straw, and a platen having a flat straw-engaging face sloping 79

with respect to the cutting edge for supporting the straw while being cut.

9. A cut-off mechanism comprising in combination with means for feeding a straw continuously, a knife having a cutting edge moving transversely to the path of the straw, and a platen having a flat straw-engaging face sloping with respect to the cutting edge and partly upon opposite sides of the knife for supporting the straw while being cut.

10. A cut-off mechanism comprising in combination with means for feeding a straw continuously, a reciprocating carriage, a knife mounted upon said carriage to reciprocate therewith, and a platen rigidly supported by said carriage adjacent the knife for reciprocating simultaneously with said knife and carriage and for supporting the straw against lateral movement in one direction and permitting lateral movement of the straw with respect to the platen in another direction while the straw is being cut.

11. A cut-off mechanism comprising in combination with means for feeding a straw continuously, a knife, and means having straw receiving and delivery ends both interposed between the feeding means and said knife for dipping the straw at predetermined intervals, the delivery end of said interposed means being offset from the plane of the knife a distance greater than the amplitude of dipping of said delivery end thereby permitting the straw to assume a curvature between said delivery end and the knife.

12. A cut-off mechanism comprising in combination with means for feeding a straw continuously, a knife having a cutting edge moving transversely to the path of the straw, and means for dipping the straw into the knife, said means comprising a rocker-shaft and means for effecting a lateral transition and simultaneous rotation of said shaft.

13. A cut-off mechanism comprising in combination with means for feeding a straw continuously, a knife having a cutting edge moving transversely to the path of the straw, and means for dipping the straw into the knife, said means comprising a rocker-shaft and means for effecting a lateral transition and simultaneous rotation of said shaft and a straw guide off-set from said shaft and connected therewith so as to be both swung and dipped.

14. A cut-off mechanism comprising in combination with means for feeding a straw continuously, a knife having a cutting edge moving transverse to the path of the straw, a cam operated lever, a shaft rotatably carried by said lever, a pinion on said shaft and a rack in mesh with said pinion whereby swinging the arm obtains a body transition of the shaft and a simultaneous rotation thereof.

15. A cut-off mechanism comprising in combination with means for feeding a straw continuously, a knife having a cutting edge moving transverse to the path of the straw, a cam operated lever, a shaft rotatably carried by said lever, a pinion on said shaft and a rack in mesh with said pinion and resiliently pressing toward the pinion whereby swinging the arm obtains a body transition of the shaft and a simultaneous rotation thereof.

16. A cut-off mechanism comprising in combination with means for feeding a straw continuously, a reciprocating carriage, a knife mounted upon said carriage to reciprocate therewith, means supported independently of said carriage for guiding and dipping the straw at predetermined intervals into the cutting path of the knife, and a platen supported by said carriage adjacent the knife for reciprocating simultaneously with said knife and carriage and for supporting the straw while the straw is being cut.

17. A cut-off mechanism comprising in combination with means for feeding a straw continuously, a reciprocating carriage, a knife mounted upon said carriage to reciprocate therewith, means supported independently of said carriage for guiding and dipping the straw at predetermined intervals into the cutting path of the knife, and a platen supported by and in fixed relation to said carriage adjacent the knife for reciprocating simultaneously with said knife and carriage and for supporting the straw while the straw is being cut.

18. A cut-off mechanism comprising in combination with means for feeding a straw continuously, a reciprocating carriage, a knife mounted upon said carriage to reciprocate therewith, and an open platen upon which the straw may move laterally a distance greater than the diameter of the straw, said platen supporting the straw while the straw is being cut.

19. A cut-off mechanism comprising in combination with means for feeding a straw continuously, a reciprocating carriage, a knife mounted upon said carriage to reciprocate therewith, and an open platen upon which the straw may move laterally a distance greater than the diameter of the straw, said platen having a position adjacent to the knife while the straw is being cut for supporting the straw during the cutting thereof.

20. A cut-off mechanism comprising in combination with means for feeding a straw continuously, a reciprocating carriage, a knife mounted upon said carriage to reciprocate therewith, and an open platen upon which the straw may move laterally a distance greater than the diameter of the straw, said platen being supported by said carriage adjacent the knife for reciprocating simultaneously with said knife and carriage and for supporting the straw while the straw is being cut.

21. A cut-off mechanism comprising in combination with means for feeding a straw continuously, a reciprocating carriage, a knife mounted upon said carriage to reciprocate therewith, and an open platen upon which the straw may move laterally a distance greater than the diameter of the straw, said platen being supported by and in fixed relation to said carriage adjacent the knife for reciprocating simultaneously with said knife and carriage and for supporting the straw while the straw is being cut.

22. A cut-off mechanism comprising in combination with means for feeding a tube continuously, a rotating cutter, a tubular tube guide through which said tube passes, said tube guide having a discharge end relatively far from the cutter for affording freedom of the formed tube to flex at will more than its own diameter under influence of contact with the cutter pulling the tube inwardly of the cutting edge, and means dipping the tubular tube guide to substantially the level of the edge of the cutter to engage the tube with the cutting edge and enabling the tube to be drawn inwardly by the cutter and enabling the cutting to be effected only at the rate at which the cutter pulls the tube inwardly of the cutting edge.

23. A cut-off mechanism comprising in combination with means for feeding a tube continuously, a rotating cutter, said tube being held

with relative freedom with respect to its lateral movement where crossing the cutter such that the tube may deflect at will more than its own diameter, and means for periodically engaging the tube with the edge of the cutter whereby the cutter will function to deflect the tube from its otherwise normal path and sever the tube.

24. A cut-off mechanism comprising in combination with means for rotatably feeding a tube continuously, a rotating cutter the cutting edge of which toward the tube moves in the same direction as the side of the tube toward the cutter, and means for periodically engaging the tube with the edge of the cutter whereby the tube will tend to roll in the direction of movement of the engaged portion of the cutter and the cutter will function to cooperate with the rolling of the tube to draw the same into the cutter and sever the tube.

25. A cut-off mechanism comprising in combination with means for rotatably feeding a tube continuously, a rotating cutter the cutting edge of which toward the tube moves in the same direction as the side of the tube toward the cutter, a platen adjacent the cutter and tube sloping in the direction of movement of the cutter enabling the tube to roll thereon in the direction of its rotation and thereby tend to feed the tube to the cutter.

26. A cut-off mechanism comprising in combination with means for rotatably feeding a tube continuously, a rotating cutter the cutting edge of which toward the tube moves in the same direction as the side of the tube toward the cutter, a platen adjacent the cutter and tube sloping

in the direction of movement of the cutter enabling the tube to roll thereon in the direction of its rotation and thereby tend to feed the tube to the cutter, and means for periodically engaging the tube with the edge of the cutter whereby the tube will tend to roll in the direction of movement of the engaged portion of the cutter and the cutter will function to cooperate with the rolling of the tube to draw the same into the cutter and sever the tube.

27. A cut-off mechanism comprising in combination with means for rotatably feeding a tube continuously, a rotating cutter the cutting edge of which toward the tube moves in the same direction as the side of the tube toward the cutter, and means for periodically engaging the tube with the edge of the cutter whereby the tube will tend to roll in the direction of movement of the engaged portion of the cutter and the cutter will function to cooperate with the rolling of the tube to draw the same into the cutter and sever the tube, and a platen providing one portion thereof engaged by the tube as the tube first engages the cutter and a second portion engaged by the tube as the cutter substantially severs the tube, the first said portion enforcing a greater movement on the tube radially of the cutter than the second portion and the second portion permitting a greater relative movement of the tube in the direction of movement of the cutter than the first said portion whereby the lateral deflection of the tube is speeded for the final severing thereof.

KARL E. GARLING. 35
